METHOD FOR ELIMINATING FOAMING IN
THE RECOVERY OF SULFURIC ACID FROM
AN OLEFIN RECOVERY OPERATIONJohn H. Cone, Goose Creek, Tex., assignor to
Standard Oil Development Company, a cor-
poration of Delaware

Application June 4, 1945, Serial No. 597,404

8 Claims. (Cl. 260—677)

1
The present invention is directed to a method for concentrating relatively weak sulfuric acid which previously has been employed for treating hydrocarbons.

More particularly, the present invention is directed to a process comprising the treatment of low molecular weight hydrocarbons including olefins with sulfuric acid to form an extract, the recovery of absorbed and reacted hydrocarbons from the extract and the concentration of the recovered acid, wherein unsaturated cyclic hydrocarbons are employed to prevent foaming of the extract and of the sulfuric acid undergoing concentration.

It is conventional to the art to recover low molecular weight olefins from a hydrocarbon mixture by contacting the mixture with 65% sulfuric acid. As an example of a typical operation, a hydrocarbon feed stock including normal butane, isobutylene and normal butylene may be brought into contact with sulfuric acid in a reaction zone under a pressure substantially in excess of atmospheric in order to form an extract. The extract is sent to a vent drum where its pressure is reduced to substantially atmospheric with the resultant release of the butanes and butylenes, and the remainder is then sent to a regenerator where polymers, alcohols and olefins resulting from the reaction of the sulfuric acid with the hydrocarbon mixture are separated as overhead fractions and the acid is regenerated and an acid of 45% strength recovered. The acid is removed from the regenerator to an acid concentrator where its strength is increased to 65% and is then returned to the reaction zone of the system. In conventional operations, a substantial foaming is encountered in the vent drum, the regenerator and in the acid concentrator and this foaming reduces the capacity of these portions of the system.

In accordance with the present invention foaming in the vent drum, regenerator and acid concentrator is eliminated by adding to the sulfuric acid being circulated in the system a small amount of material separated as the extract when contacting a petroleum fraction containing unsaturated cyclic hydrocarbon constituents with a selective solvent. These constituents derive from a petroleum fraction containing unsaturated cyclic hydrocarbons and are preferably added to the sulfuric acid as it is being passed from the reaction zone to the vent drum, but alternatively the constituents may be added to the stream of sulfuric acid flowing through

2
other portions of the system in order to eliminate or prevent foaming in the system.

The treatment of a crude petroleum or a petroleum fraction with a selective solvent to separate it into a more unsaturated component and a more saturated component is well known to the art. As examples of well-known selective solvents suitable for this purpose may be mentioned phenol, sulfur dioxide, furfural and BB' dichloroethyl ether. As the selective solvent process is conventionally practiced, the material insoluble in the solvent and separated therefrom by gravity settling is designated as the raffinate fraction while the material dissolved in the selective solvent is designated as the extract fraction. In accordance with the present invention, it has been found desirable to employ as the crude petroleum or petroleum fraction employed as a feed stock in the solvent extraction step a so-called naphthenic base oil. Such petroliums are commonly obtained from the Gulf Coast area of the United States and contain substantial amounts of naphthenic constituents or aromatic constituents or a mixture of naphthenic and aromatic constituents.

As a specific example of a material obtained by extracting a petroleum fraction including substantial amounts of cyclic hydrocarbons with a selective solvent may be mentioned a hydrocarbon extract obtained by contacting a Coastal distillate fraction with phenol. Such a fraction, commercially designated at 75-phenol extract, has the following physical characteristics:

TABLE I	
Gravity, API	15.5
Flash, O. C. °F	325
Viscosity at 100° F SSU	160
Viscosity at 210° F SSU	39.2
40 Pour (ASTM) °F	—35

Distillation at 10 mm. Hg. pressure	
IBP °F	330
5% at °F	350
45 10% at °F	357
20% at °F	370
30% at °F	383
40% at °F	393
50% at °F	404
50 60% at °F	419
70% at °F	437
80% at °F	468
90% at °F	516
95% at °F	564
55 FBP at °F	600

The 75-phenol extract was obtained by extracting a light lubricating oil fraction separated from a Gulf Coast crude petroleum. The light lubricating oil fraction had the following characteristics:

TABLE II

Gravity API	25.8
Flash OC, °F.	320
Viscosity at 100° F. SSU	82
Viscosity at 210° F. SSU	37.2
Pour (ASTM) °F.	-35

It will be understood that the amount of the constituents separated from a crude petroleum or petroleum fraction by contacting the fraction with the selective solvent which is used for suppressing the foaming may be varied over a substantial range when used in a sulfuric acid-hydrocarbon mixture. Under extreme conditions it may be desirable to employ as much as 2 gallons of the extract per 20,000 pounds of sulfuric acid hydrocarbon mixture while under other conditions 1 pint of extract per 20,000 pounds of the sulfuric acid hydrocarbon mixture may be found adequate. Under normal operating conditions the 75-phenol extract having the characteristics given above has been found to produce satisfactory results in a solution including 65% sulfuric acid and isobutylene when used in amounts in the proportion of 1 quart of the 75-phenol extract per 20,000 pounds of the sulfuric acid isobutylene solution. It is also to be understood that a number of petroleum fractions are satisfactory as a charge stock from which the constituents soluble in a selective solvent may be obtained. For example, middle distillates, heavier lubricating fractions and fractions extending from the gasoline boiling range to asphalts may be brought into contact with a selective solvent for the recovery therefrom of constituents which will be suitable for suppressing foam in sulfuric acid-hydrocarbon mixtures.

The invention will now be described in greater detail in conjunction with the drawing in which the single figure is in the form of a flow sheet illustrating a preferred modification of the present invention.

The system shown in the drawing may be described generally as involving a reaction zone, an acid regenerating zone and an acid concentrating zone. These three zones are indicated in the drawing by dashed rectangles, the reaction zone being designated by A, the acid regenerating zone by B and the acid concentrating zone by C.

The reaction zone A includes a first stage reactor 11, a first stage settling drum 12, a second stage reactor 13 and a second stage settling drum 14. The acid regenerating zone B includes vent drum 15 and regenerator vessel 16. The acid concentrator zone C includes an acid concentrator shown as a single vessel 17 and an accumulator vessel 55. The feed hydrocarbons are passed to the system from storage vessel 18.

In the reaction or absorption zone A the feed hydrocarbons flow through the first and second stages in sequence and the sulfuric acid is passed into the second stage to form an extract therein, the extract is taken from the second stage to the first stage where it is enriched and the resulting enriched extract is sent through the acid regeneration and acid concentration zones. The vent drum 15 is arranged between settling vessel 12 and regenerator 16 in order to allow the release of pressure of the extract before it is sent to the regenerator.

In order to prevent foaming of the acid in vent drum 15, regenerator 16 and acid concentrator 17, constituents obtained as an extract fraction when contacting a selective solvent with 5 a petroleum fraction comprising a substantial amount of cyclic hydrocarbons is added to the circulating stream of acid. In the drawing the means for adding the constituents derived from petroleum is indicated as inlet 19 and for convenience this material is designated in the drawing 10 by the legend "cyclic petroleum constituents" although it will be understood that these constituents may include other materials in addition to cyclic materials which are dissolved in the selective solvent when it is brought into contact with the crude petroleum or petroleum fraction.

The hydrocarbon feed stock is passed from vessel 18 by line 20 in which is arranged a pump 20 and heat exchanger 22 and discharges through distributing lines 23 and 24 into first stage reactor 11. The liquid from the bottom of reactor 11 is withdrawn through line 25 and the stream split, with a portion passing through line 26 to first stage settling zone 12 and the remainder being recycled to line 20 via line 27. To the extract flowing through line 21 is added extract withdrawn through line 28 from the second stage settling zone 14. The extract withdrawn from drum 14 and the extract withdrawn from the first stage reactor 11 are mixed in line 29 and the mixture of extract is then discharged into the hydrocarbon stream in line 20. The hydrocarbon vapors in reactor vessel 11 which are not absorbed or do not react with sulfuric acid therein 30 are removed as overhead through line 29 and discharged into the upper portion of settling drum 12. The unabsorbed hydrocarbons pass from settling drum 12 through line 30, containing heat exchanger 31, and discharge through line 32 and 33 in the second stage reactor 13. Extract from the lower portion of second stage reactor 13 is withdrawn through line 34 and the stream split, with a portion passing through line 40 35 to second stage settling zone 14 and the remainder passing through pump 36 and discharging into the hydrocarbon stream passing through line 30. The regenerated and reconcentrated sulfuric acid is added to the stream flowing in line 50 34 by line 37.

Unabsorbed and unreacted hydrocarbon vapors from the second stage reactor 13 pass through line 38 to second stage settling vessel 14 and the unreacted and unabsorbed hydrocarbons from 55 vessel 14 are withdrawn from outlet 39.

Settling drum 12 is operated under superatmospheric pressure and to recover hydrocarbons from the extract, it is desirable first to release the pressure from the extract and subsequently subject it to a heating operation. In the drawing, the extract from settling vessel 12 is withdrawn through line 40 to vent drum 15 where the pressure is released to atmospheric by vent line 41, passes from drum 15 via line 42 containing pump 43 and is discharged into regenerator tower 16. Hydrocarbons in vaporous condition are removed from tower 16 as overhead through outlet 45 and pass into scrubber 46 where they come into contact with caustic introduced into the scrubber through inlet 47. Vapors from scrubber 46 pass through outlet 48, cooler 49 and discharge into accumulator 50. Uncondensed constituents are removed in gaseous form from accumulator 50 through outlet 51 while condensate is removed 70 75 through outlet 52 containing pump 53. After

the condensate passes through pump 53, the stream is split and a first portion is passed through line 54 and discharged as a scrubbing medium in scrubber 46, a second portion is passed through line 55 and again divided with one portion discharging through line 56 into regenerator 16 and the remaining portion passing through line 57 and heater 58 and discharging into regenerator 16. A portion of the stream in line 52 is withdrawn through line 60 and mingled in line 10 with the bottoms withdrawn from scrubber 59 with the bottoms withdrawn from scrubber 46. The mixture in line 59 includes alcohol and polymer and is withdrawn from the system to a suitable arrangement, not shown, for recovering these materials.

The acid is withdrawn from the bottom of regenerator tower 16 through line 44 and passes to acid concentrator 17. In this vessel the acid is heated by steam passing through coil 62 and water vapor is driven from the acid and discharged through outlet 63. The acid from vessel 17 is discharged into an accumulator vessel 65 containing a cooling coil 66 and vent 67. From vessel 65 the regenerated acid is passed through lines 37 and 34 to the hydrocarbon stream in line 25 30. In order to replace acid lost in the operation, make-up acid may be introduced through inlet line 68 to the stream of regenerated acid.

As an example illustrating the operation of the process in the drawing, the feed stock withdrawn from vessel 18 may consist of 50% iso and normal butane, 32% normal butylene and 18% isobutylene. The first stage reactor vessel may be operated at a temperature of 100° F. and a pressure of approximately 40 pounds per square inch while a second stage reactor 13 may be operated at a temperature of 70° F. and under a pressure of 135 pounds per square inch. Under these conditions, the pressure in first stage settling zone 12 is approximately 135 pounds per square inch; the pressure is released to atmospheric as the extract is passed into vent drum 15. The regenerator 16 may be operated with a bottom temperature of 240° F. and a top temperature of 160° F. with acid of a concentration of approximately 45% withdrawn therefrom through line 44. The acid may be concentrated in unit 17 to a strength of approximately 65%.

A plant having the reactor zone, regenerator zone and acid concentrator zone designed to operate under the temperature and pressure conditions given above was designed to regenerate and concentrate 20,000 pounds of sulfuric acid-hydrocarbon extract per hour. Prior to the addition of the unsaturated hydrocarbon material extracted from a crude petroleum or petroleum fraction in accordance with the present invention, severe foaming was experienced in the vent drum, acid regenerator and acid concentrator to such an extent that these units could be operated only at approximately one-half the design capacity. Upon the addition of an extract obtained from petroleum oil to the sulfuric acid-hydrocarbon mixture being charged to vent drum 15, the foaming was eliminated and the output of these units increased to the design capacity. Under normal operations, one quart per hour of an extract derived from petroleum added to the stream of sulfuric acid-hydrocarbon charged to the vent drum satisfactorily reduces foaming. The acid concentrator 17 is separated into four compartments in the plant described above and the acid withdrawn from the last compartment appears to be free from oil even upon settling; this indicates that the extract is swept from the reconcentrated

acid with the water vapors in the acid concentrator unit.

Having fully described and illustrated the present invention, what I desire to claim is:

5. In the treatment of an extract resulting from the contact of sulfuric acid with low molecular weight olefins, the steps of incorporating in the extract unsaturated cyclic hydrocarbons obtained by bringing a petroleum fraction including said unsaturated cyclic hydrocarbons into contact with a selective solvent capable of dissolving said cyclic hydrocarbons from said petroleum fraction, said cyclic hydrocarbons being added in an amount sufficient to eliminate foaming in the extract upon heating under a reduced pressure and subsequently heating the extract under a reduced pressure to recover olefins therefrom.

20. A method in accordance with claim 1 in which the fraction is added to the extract in the proportion of approximately one quart per 20,000 pounds of extract.

25. In a method involving the steps of contacting a predominantly C₄ hydrocarbon feed stock comprising olefins with sulfuric acid under super-atmospheric pressure in a reaction zone to form an extract, removing the extract from the reaction zone to a regeneration zone, heating the extract and reducing the pressure imposed thereon in the reaction zone to separate it into a hydrocarbon fraction and an acid fraction and recycling of the recovered sulfuric acid to the reaction zone, the step of adding to the circulating sulfuric acid stream unsaturated cyclic hydrocarbons obtained by bringing a petroleum fraction containing said cyclic hydrocarbons into contact with a selective solvent capable of dissolving said cyclic hydrocarbons from said petroleum fraction, said cyclic hydrocarbons being added in an amount substantially to eliminate foam in the regeneration zone.

30. A method in accordance with claim 3 in which said constituents are added to the circulating sulfuric acid stream in an amount of the order of one quart to 20,000 pounds of sulfuric acid extract passed to the regeneration zone.

35. In a method including the steps of contacting a hydrocarbon stream comprising a substantial portion of C₄ hydrocarbons and appreciable amounts of olefin with sulfuric acid in a reaction zone under conditions to form an extract, separating the resulting extract in an acid regeneration zone into a hydrocarbon fraction and an acid fraction of approximately the same concentration as that in the reaction zone, the step of adding 40 to the extract being sent from the reaction zone to the regeneration zone unsaturated cyclic materials derived from petroleum containing them by extraction of said petroleum with a selective solvent for said cyclic materials, said cyclic materials being added in an amount sufficient to prevent foaming in said regeneration zone.

45. A method in accordance with claim 5 in which the constituents are present in an amount of the order of 1 quart per 20,000 pounds of extract passed to the regeneration zone.

50. A method in accordance with claim 5 in which the constituents are obtained by contacting a distillate derived from a naphthenic base crude oil in the lubricating oil viscosity range with a selective solvent.

55. A method in accordance with claim 5 in which the constituents are obtained by contacting a distillate fraction having a viscosity in the lubricating oil range and derived from a naphthenic petroleum by dissolving them in a selective

60. A method in accordance with claim 5 in which the constituents are obtained by contacting a distillate fraction having a viscosity in the lubricating oil range and derived from a naph-

65. A method in accordance with claim 5 in which the constituents are obtained by contacting a distillate fraction having a viscosity in the lubricating oil range and derived from a naph-

70. A method in accordance with claim 5 in which the constituents are obtained by contacting a distillate fraction having a viscosity in the lubricating oil range and derived from a naph-

75. A method in accordance with claim 5 in which the constituents are obtained by contacting a distillate fraction having a viscosity in the lubricating oil range and derived from a naph-

solvent and in which approximately 1 quart of the constituents are added to 20,000 pounds of the sulfuric acid extract.
